SEALING STRIP FOR PULP AND OTHER
TYPES OF SCREEN PLATESHenry William Downs, Jr., Lenoxville,
Quebec, Canada

Application March 26, 1947, Serial No. 737,398

1 Claim. (Cl. 92—30)

1
The invention relates to improvements in sealing strips for pulp and other types of screen plates as described in the present specification and illustrated in the accompanying drawings that form a part of the same.

The invention consists essentially of the novel features of construction as specifically pointed out in the claims for novelty following a description in detail of an acceptable form of the invention.

The objects of the invention are to provide a sealing strip for screen plates which will seal the joint between the edge of a screen plate and the wall of a vat; to devise a sealing strip which will permit easy removal or replacement of screen plates in a vat; to provide a sanitary means of securing screen plates in a vat and render same readily accessible for washing and cleaning; to construct a sealing strip which can be tightened down securely on a screen plate, and at the same time, be drawn in snugly against the wall of a vat; to devise a sealing strip which is simple in design and inexpensive to manufacture; to construct a sealing strip which has a positive locking device for holding same in position in a vat; and generally to provide a sealing strip which will be durable and efficient for its purpose.

In the drawings:

Figure 1 is a perspective fragmentary view showing a portion of the sealing strip and screen plate in an assembled position.

Figure 2 is a side sectional view as taken on the line 2—2 in Figure 1.

Figure 3 is a plan sectional view as taken on the line 3—3 in Figure 1.

Figure 4 is a detail showing a plan view of the guide member for the locking device.

Figure 5 is a front view of Figure 4.

Figure 6 is a side sectional view as taken on the line 6—6 in Figure 4.

Figure 7 is a detail showing a plan view of the adjusting bolt for the locking device.

Figure 8 is a front view of Figure 7.

Figure 9 is a detail showing a plan view of the locking head.

Figure 10 is a front view of Figure 9.

Figure 11 is a side sectional view as taken on the line 11—11 in Figure 9.

Figure 12 is a detail showing a plan view of the lock plate.

Figure 13 is a front view of Figure 12.

Figure 14 is a side sectional view as taken on the line 14—14 in Figure 12.

Like numerals of reference indicate corresponding parts in the various figures.

2

Referring to the drawings the sealing strip consists of a longitudinal strip or strip member as indicated by the numeral 20. This strip is of a predetermined width and thickness to accommodate the locking devices which are placed at intervals along the entire length of same. The strip 20 is adapted to be secured to the side wall of the vat as indicated by the numeral 21. The support frame or shoulder strip 22 is fitted in an elongated recess in the side wall 21 of the vat and suitably secured thereto, thus forming a ledge on the inner face of same. This support frame 22 provides a means of supporting the screen plate 23, the latter resting on the upper edge of same.

The side wall 21 has a plurality of cutouts or apertures 25 in same which are suitably spaced so as to coincide with the fastening devices 24 which are mounted at intervals in the longitudinal strip 20. A lock plate 26 is mounted over each of the apertures 25 in the side wall 21 and fixedly secured thereto. The lock plate 26 is accommodated in a recessed portion around the aperture 25, thus permitting the outer face 26A of same to be flush with the inner face of the side wall 21. This lock plate has an aperture or cutout 27 which may be square or rectangular in shape with inwardly protruding edges 28 on three sides thereof. The remaining edge 29 of the aperture 27 has only sufficient thickness for strength and the tapered or wedge shaped portion 30 extends upward and therefrom. This tapered portion is formed actually by increasing the thickness of that portion of the lock plate as it recedes from the aperture 27. The tapered portion 30 is in a parallel inclined plane with respect to the outer face 26A of the lock plate 26, thus providing a surface with which the locking head 31 may engage.

The locking head 31 forms a part of the locking device 24 and is slidably accommodated in same. The main portion 32 of the locking head 31 has an internally threaded portion 33 extending vertically therethrough. This main portion 32 of the locking head has a pair of flanges or lugs 34 protruding therefrom. These flanges 34 form an integral part of the main portion 32 and extend vertically the entire length of same. The lower portion 35 of the locking head 31 extends outward horizontally a predetermined distance from the main portion 32 of same, and then extends vertically upward therefrom to form a catch, or lip portion 36. The inner face 37 of this lip portion 36 extends outward and upward from the lower portion 35 of the locking head, thus

providing a tapered lip which engages with the tapered portion 30 of the lock plate 26.

The strip member 20 has a cutout or recessed portion 39 in the inner face 40 of same which accommodates the locking head 31 and permits the guide member 41 which encloses this recessed portion to be flush with this inner face 40. The guide member 41 is fixedly secured to the strip member 20 by flat head screws or other suitable means. This guide member 41 is L-shaped having an elongated slot 42 in the vertical portion 43 of same. The recessed portion 39 in the strip member 20 in cooperation with the vertical portion 43 of the guide member 41 form a vertical passage having a pair of grooves therein and in which the locking head 31 is slidably fitted. The flanges 34 of the locking head travel in this pair of grooves, thus maintaining same substantially in position as it slides upward and downward with respect to the strip member 20. The lip portion 36 of the locking head 31 projects through the slot 42 in the guide member 41 thus being in position for engagement with the tapered portion 30 of the lock plate 26.

The horizontal portion 44 of the guide member 41 rests on the upper edge of the strip member 20 and has a hole 45 in same.

The adjusting bolt 46 consists of a threaded portion 47 which has a shoulder portion 48 formed toward the upper part of same. The upper end of the adjusting bolt 46 has a square head 49 which is smaller than the shoulder portion 48. The threaded portion 47 of the adjusting bolt 46 extends through the hole 45 in the guide member 41 and engages the threaded portion 33 in the locking head 31.

As the adjusting bolt 46 is threaded into the locking head 31 the shoulder portion 48 bears on the upper surface of the guide member 41 thus raising the locking head. While in this instance the adjusting screw has a square head it could be provided with a hexagon or type of head adaptable to be turned by a key without generally affecting the advantages of the invention.

The side wall of the vat has a recessed portion 52 which extends above the top level of the adjusting bolt 46, the recess providing necessary space for the application of a key or other suitable implement to the bolt.

The strip member 20 has a recessed portion 50 along the lower edge of same, which accommodates the packing strip 51 which is slidably secured therein. This packing strip extends the entire length of the strip member 20 and protrudes past the inner face 40 of same. The packing strip 51 also extends downward a suitable distance below the lower edge of this strip member.

In the operation of the invention the screen plate 23 is placed in position on the support frame 22. The strip member 20 which accommodates a plurality of locking devices 24 and the packing strip 51 is then placed in position along the upper edge of the screen plate adjacent to the side wall 21 of the vat. The adjusting bolts 46 are loosened sufficiently to allow the lip portion 36 of the locking head 31 in each of the locking devices 24 to be inserted in the aperture 27 of the lock plates 26. The adjusting bolts 46 are then tightened raising each of the locking heads 31 so that their respective lip portions 36 engage with the tapered portion 30 of each of the lock plates 26. As the inner face 37 of these lip portions 36 are tapered to coincide with the tapered portion 30 of the lock plates 26 the wedging

action forces the packing strip 51 tightly against the side wall 21 of the vat and the upper edge of the screen plate 23 simultaneously.

It will be seen from the foregoing that a sealing strip has been designed that will provide a leak-proof means of securing screen plates substantially in position and at the same time render the latter easily removable for replacement, cleaning and the like.

What I claim is:

In a sealing strip for pulp and other types of screen plates, a unit adapted to hold a screen plate in position on a ledge secured along the inner wall of a vat, said unit being removably attachable to the wall of the vat and comprising a longitudinal member having a recess extending along the bottom face at the inner edge thereof and a packing strip located in the recess and projecting beyond the bottom face and the inner edge of the member, thereby providing the same with two working surfaces, and said packing strip being brought in direct contact with the top of the screen plate along its inner edge as positioned on the supporting ledge, effectively sealing the same with respect to the top surface of the screen and with the inner wall of the vat, locking means for maintaining said unit to the wall of the vat over the screen plate and an adjusting means on the longitudinal member of said unit adapted to be manipulated and co-act with the locking means for moving said unit slightly downward and inward to position said packing strip to the screen plate and against the wall of the vat, the said locking means comprising a lock plate mounted on the wall of the vat over an aperture therein, the lock plate having cutout therein three side edges of which protrude inwardly, a tapering or wedge-shaped portion being formed on the other side of the cutout and extending upwardly, a locking head slidably located in a recess formed in the rear face of said longitudinal member of said unit and having a vertical threaded portion and an outwardly extending and upwardly formed lip portion adapted to engage the said tapered edge of the cutout in said lock plate upon the said unit being positioned to the wall of the vat, said adjusting means consisting of a threaded bolt extending down into the recess in said longitudinal member and engaging the threaded portion of said locking head adapting the same to be raised to bring the lip portion of the locking head into locking engagement with the tapering side section of the cutout in the lock plate thereby effectively locking said unit to the wall of the vat and at the same time acting to move said unit slightly downward and inward towards the wall of the vat against the same and the screen plate.

HENRY WILLIAM DOWNS, JR.
